UNITED STATES PATENT OFFICE.

VERALDO CALZETTI, OF PARMA, ITALY.

GYMNAStic APPARATUS.

Application filed April 9, 1924. Serial No. 705,399.

To all whom it may concern:

Be it known that I, VERALDO CALZETTI, a subject of the King of Italy, residing at Parma, Province of Parma, Italy, have invented certain new and useful Improvements in and Relating to a Gymnastic Apparatus, of which the following is a specification.

The present invention relates to a gymnastic apparatus particularly suitable for 10 rowing training.

The invention comprises an embodiment of parts and arrangement of organs suitable for the development of the limbs as would be by the ordinary rowing practice.

15 The invention will be described with reference to the annexed drawings and pointed out in the appended claim.

In the drawing:

Fig. 1 is a side elevational view of the apparatus.

Fig. 2 is a partial plan view of the same. Fig. 3 is a partial front view.

The frame of the apparatus comprises the girders —1— and the transversals —2— 25 —4— —3—.

Guides —5— —5— are secured longitudinally to said frame and carry the seat —7— provided with rollers —8—.

9 is a foot-board, 10 are the legs of the 30 apparatus.

On the side girders —1— are mounted the standards —11— and slots —14— are provided in said girders to allow a suitable positioning of said standards and securing 35 the same by means of bolts —12— and nuts —13—.

Said standards are provided with ear-supports —15— the outer edge of which have ratchet-teeth —16—.

40 Supporting iron frames —19— are pivotally connected to said ears —15— through ears —18— and bolts —17—.

The outer sides —20— of said frames are provided with column-supports —21— to 45 which standards —23— are pivoted by their end-sides.

Each of said standards —23— is provided with apertures at the middle point to receive a bolt —24— forming a pivot connection for one end of a lever —26—.

The levers —26— are indicated in dotted lines and are provided with tie-ring —31— having a hook —32— for the connection to one end of a spring —33— the other end of which is connected to the eyelet of bolt 55 —34— secured to the transversal —2— and projecting therefrom.

The rings —31— are generally secured to the levers —26— but their position may be varied according to necessity.

60 The running stroke of the seat —7— may be limited by a transversal rod —35— engaging the teeth of racks —36— secured to the guides —5—.

The apparatus is operated as follows:

65 The operator stands or sits on the seat —7— and according to his position and height, the frames —19— are adjusted in position by swinging them around the pivots —17—. Pawls —27— pivoted to said frames and engaging by a terminal hook, the ratchet-teeth —16— on ears —15—, hold the frames in position.

Said pawls are secured to a common rod —28— with a handle —30— while springs 75 —29— are tensioning said rod to keep the pawls in contact with the racks.

Having now particularly described the nature of my invention and the manner in which the same should be performed I 80 claim:

A gymnastic apparatus comprising in combination a frame with longitudinal and transverse girders, longitudinal guides for a rolling seat, pivotally adjustable frames 85 on the longitudinal girders of said frame, standards pivotally mounted on the outer sides of said frames, levers pivotally connected to said standards orthogonally to the rotation-axis of said standards, spring connections between a point of said levers and a point of the main-frame.

90 In testimony whereof I affixed my signature in presence of two witnesses.

VERALDO CALZETTI.

Witnesses:

W. ORESTE P. CLAMO,
A. FUCHIO.
